DESIGN FOR A GAME BOARD

Omar P. Goslin, Bronxville, N. Y.

Application April 24, 1942, Serial No. 106,683

Term of patent 3½ years

To all whom it may concern:

Be it known that I, Omar P. Goslin, a citizen of the United States and resident of Bronxville, in the county of Westchester and State of New York, have invented a new, original, and ornamental Design for a Game Board, of which the following is a specification, reference being had to the accompanying drawing, forming a part thereof, and of which Figure 1 is a plan view of a game board showing my new design, Fig. 2 is an edge view at one side thereof, and Fig. 3 is an edge view at the opposite side thereof.

I claim:

The ornamental design for a game board, substantially as shown.

OMAR P. GOSLIN.
